IGNITION MIXTURES AND ELECTRIC INITIATORS

David T. Zebree, Kingston, N.Y., assignor to Hercules Powder Company, Wilmington, Del., a corporation of Delaware

Application March 30, 1956, Serial No. 575,026

19 Claims. (Cl. 52—2)

This invention relates to ignition mixtures particularly utilizable in electric blasting caps. In one aspect this invention relates to a detonating method employing such ignition mixtures. In still another aspect this invention relates to electric initiating devices and more particularly to delay electric initiating devices with ignition assemblies of greatly enhanced ignition characteristics. This application is a continuation-in-part of my copending application, Serial Number 78,383, filed February 25, 1949, now abandoned.

In the manufacture of delay electric initiating devices one of the most commonly used and most satisfactory igniton compositions is a mixture of finely-divided lead and selenium. These mixtures are substantially gasless during combustion, and, for the most part, have proved most satisfactory in igniting fuse elements containing delay trains composed of such difficultly ignitable mixtures as barium peroxide-selenium.

A very substantial problem has been encountered, however, due to the deterioration in quality of these mixtures which results from the oxidation of the lead. This deterioration is most pronounced during warm weather storage and its rate is accentuated by the presence of moisture. Such deterioration has two very undesirable effects on the performance of a delay electric blasting initiator which flow directly from the diminution in calorific content of the mixture due to the progressive oxidation. First, irregularity in firing times results with a consequent overlapping among delay periods in series firing. Second, actual fuse ignition failures result in numbers directly proportional to the degree of oxidation of the lead which has taken place. As a result of such deterioration, it has been necessary to purchase special and more expensive grades of lead powder which have a very low initial oxide content. It is then necessary to exercise meticulous care in the handling and storage of both the ignition mixture and the completed initiating devices. Despite all such precautions, however, a progressive deterioration in quality may still take place in time, with the undesirable consequences above set forth.

A further problem has been encountered when delay electric blasting initiating devices containing lead-selenium mixtures are fired in an inverted position. Even when the ignition mixtures contain no appreciable oxide content, occasional failures are still encountered during inverted firing due to the tendency of the lead-selenium mixture to shrink during combustion. The failures are due to an actual shrinking away from the delay fuse to the extent that the ignited ignition powder does not make sufficient contact for ignition of the delay train.

Therefore, an object of this invention is a delay electric initiating device of greatly improved performance which is not subject to failure due to deterioration of its ignition mixture. Another object of this invention is a delay electric initiating device comprising an ignition mixture containing lead and selenium which is not subject to irregularity in firing time due to improper ignition. Another object of this invention is a delay electric initiating device

comprising an ignition mixture containing lead and selenium which is not subject to ignition failures during inverted firing. Still another object is to provide lead-selenium ignition mixtures exhibiting improved ignition characteristics. Yet another object is to provide a method for effecting ignition in the detonation of an explosive employing a primer. Other aspects and objects will be apparent from the accompanying disclosure and the appended claims.

10 In accordance with this invention an ignition mixture is provided which comprises lead and selenium in ignitable proportions, as the major ingredients, and an amount of silicon capable of imparting increased heat of combustion when said lead and selenium are burned. Still in 15 accordance with this invention is provided an electric initiating device having in combination a delay fuse element and a loose ignition mixture in contact with the delay fuse element, said mixture comprising lead and selenium as the major ingredients and an amount of silicon capable of imparting increased heat of combustion when said lead and selenium are burned. Further, in accordance with this invention is provided a method for effecting detonation of a primer composition in a blasting cap, comprising placing an ignition mixture in communication 20 with said primer, in said cap, so as to effect detonation of said primer responsive to heat formed when said mixture is burned, said ignition mixture comprising lead and selenium in ignitable proportions, as the major ingredients, and an amount of silicon capable of imparting increased heat of combustion when said lead and selenium are burned, and igniting said mixture.

25 Although it is within the scope of my invention to utilize any ignitable proportions of lead and selenium, i.e., capable of undergoing combustion when contacted with a heated bridge wire as discussed hereinafter, it is now preferred for optimum results that the lead and selenium be present in the mixture in substantially stoichiometric proportions. Such a chemically equivalent mixture contains, by weight, 72.4% lead and 27.6% selenium. However, mixtures containing any suitable proportions generally between about 64% and about 80% lead and between 20% and 36% selenium can be employed.

30 Any amount of silicon can be employed in the practice of this invention which is capable of increasing heat of combustion when the lead and selenium are burned. Generally such amount is within the range of about 0.3 to 20 wt. percent of the ignition mixture, from about 1 to 5 percent being now preferred. The upper limit of silicon concentration will be set by its effect on the sensitivity of the ignition mixture, i.e., by its tendency to desensitize the mixture, which may take place at concentrations somewhat above 20 percent, dependent upon the specific lead-selenium proportions utilized.

35 Having generally described the present invention, a more specific description is presented with reference to the accompanying drawing which represents a sectional view of a delay electric blasting cap in accordance with one embodiment of the invention.

40 The drawing represents a ventless delay electric blasting cap comprising a bronze shell 1 into the bottom of which is pressed a base charge 2 of pentaerythritol tetranitrate. Above the base charge is a priming explosive 3, in this instance containing 75% diazodinitrophenol and 25% potassium chlorate. This mixture is 45 slightly pressed by a delay fuse element comprising a mixture of 84% barium peroxide and 16% powdered selenium as the fuse powder 4 compressed to the proper density in a lead tube 5. A loose charge of ignition mixture 6 is superimposed on the fuse element. The ignition mixture is composed of finely-divided lead and selenium (72.4-27.6)/silicon in a ratio of 98/2. A bridge wire 7 is affixed to the terminal ends of a pair of lead

wires 8 which are supported by a sulfur ignition plug 9. Above the plug is a layer of waterproofing material 10 and a layer of sulfur 11.

Having now described and illustrated the invention, the following examples are given for purposes of further illustration.

Example 1

Ventless delay electric blasting initiators were constructed similar to that shown in the drawing. More specifically, the shell was of bronze with a 0.259 inch inside diameter. A base charge of 0.40 g. of pentaerythritol tetranitrate was pressed to a height of $2\frac{5}{64}$ inch. A priming charge of 0.30 g. diazodinitrophenol/potassium chlorate (75/25) was pressed on top of the base charge to a height of $2\frac{5}{64}$ inch. The fuse, $\frac{1}{4}$ inch in length, consisted of a lead tube filled with a mixture of barium peroxide-selenium in the ratio of 84/16. The superimposed ignition compound comprised lead-selenium in stoichiometric proportions (72.4-27.6%, respectively)/silicon, 98/2. This ignition compound occupied a space of $1\frac{1}{64}$ inch. A sulfur ignition plug $\frac{1}{4}$ inch long was placed over the ignition powder in such a manner that the leg wire ends, which were connected by a bridge wire, extended into the loose powder to a distance of $5\frac{1}{64}$ inch. A charge of waterproofing was placed on top of the plug and occupied a space of $3\frac{3}{64}$ inch. A $\frac{1}{2}$ -inch column of sulfur completed the cap.

One hundred eighty such caps were made and 180 others were made which were similar in all respects except that the ignition charge was lead-selenium in stoichiometric proportions. In all 360 caps a lead powder was used which had a lead oxide content of 41%. When these caps were fired, 8 of those with lead-selenium ignition mixtures failed to fire. All 180 caps having lead-selenium-silicon ignition mixtures fired normally after the predetermined period of delay.

Example 2

Ventless delay electric blasting caps were made similar to those of Example 1. Two hundred caps had lead-selenium ignition charges while another 200 caps had the lead-selenium-silicon ignition charges. In all 400, the lead powder used was of top quality with a very low oxide content. When these 400 caps were fired in an inverted position, 2 of those having lead-selenium ignition charges failed, while all those having lead-selenium-silicon charges fired normally. In the two failures, the fused ignition mixture was found to have shrunk away from the delay fuse.

Example 3

In the tabulation below are recorded the results of incorporation of 1 percent and 5 percent of silicon in a lead-selenium mixture. A lead powder was employed which had an oxide content of 41%. This oxidized powder was mixed with selenium in stoichiometric proportions (72.4% lead to 27.6% selenium) as if no oxidation had taken place. The delay electric blasting caps employed were those described in Example 1. Corresponding data for lead-selenium alone are also set forth. In each test, 25 such caps were fired in series with a firing current of one ampere.

Test	Ignition Powder	Number of Series Shot	Results	Percent Failures
1.	Pb-Se	4	10 failed	10.0
2.	Pb-Se/Si, 99/1	4	All shot	0
3.	Pb-Se/Si, 95/5	4	do	0

¹ The ignition powder burned but failed to generate enough heat to ignite the delay fuse.

The foregoing examples illustrate that the incorporation of silicon in an ignition mixture comprising lead and selenium, results in greatly enhanced performance. These results are believed due to the great affinity that

silicon has for lead oxide and to the fact its addition causes the burning ignition mixture to expand rather than contract. While the reaction between lead oxide and silicon in the presence of lead-selenium is not violent, it is exothermic. When silicon as a corrective material is used in accordance with this invention, there is no adverse effect on the performance of the ignition mixture despite the degree to which deterioration in quality of the lead-selenium mixture has taken place. To the contrary, as has been shown, the presence of as little as 2% of silicon has been found to completely compensate for the presence of as much as 41% of lead oxide.

For example, a marked improvement in lead-selenium mixtures is noted when 0.3% silicon is incorporated. When 1% silicon is incorporated, fuse ignition failures in both upright and inverted firing are eliminated. When 2% of silicon is incorporated, all aberration in firing times is eliminated. Consequently, while silicon may be incorporated up to 20% and higher without adversely affecting ignition of the delay fuse or firing time of the cap, 2% and up to 5% of silicon is generally sufficient to compensate for the formation of up to 41% of lead oxide and any contraction of the lead-selenium mixture during combustion.

While any of the usual types of delay fuse may be employed in the delay initiator embodiment of this invention, the barium peroxide-selenium type of fuse employed in the examples is preferred. Any of the normal base charges and priming explosives are also operable although pentaerythritol tetranitrate-base charges and diazodinitrophenol/potassium chlorate priming charges are preferred. The usual types of shell, plug, leg wires, and sealing compound may be used although those employed and illustrated herein are preferred.

Deterioration of lead-selenium ignition mixtures due to the oxidation of the lead, therefore, no longer constitutes a problem in the improved electric initiators of this invention. When the prescribed amounts of silicon as the corrective material are incorporated in the ignition mixture as described and illustrated, it is no longer necessary to select highest grade lead powders or to exercise meticulous care in handling or storing the ignition mixtures themselves or the completed initiators. Furthermore, the failures of delay electric initiators containing lead-selenium ignition mixtures during inverted firing are also eliminated. Delay electric initiators made in accordance with the present invention are therefore easier and less expensive to manufacture and store and exhibit greatly improved performance.

A feature of this invention is in the broad range of proportions of silicon in my ignition compositions. Thus, when employing a metal such as aluminum or magnesium as a corrective material in a lead-selenium ignition mixture to counteract presence of lead oxide therein, there is a critical relatively low maximum limit of concentration, i.e., 3%, above which a violent burning reaction takes place with development of flame which generally results in bursting of the shell and concomitant failure. Therefore, when employing aluminum or magnesium or other such flame-producing metals, there is always the inherent danger that the initiator will inadvertently contain more than the maximum allowable metal and react violently, when fired, with concomitant failure. Furthermore, manufacture of such ignition mixtures (containing aluminum or magnesium or the like) is hazardous and requires highly precise procedures and equipment for handling such materials particularly to assure that the said critical limit is not exceeded. On the other hand, although silicon present in a lead-selenium ignition mixture in a concentration of say 2-3 percent often provides an optimum amount of heat liberation, no violent burning reaction takes place when such concentration is exceeded—even to as high as 20 weight percent or higher—precluding thereby any possibility that bursting of the shell will take place.

70
75

The initiator of this invention is therefore, in all events, free from any violent burning of the ignition mixture and concomitant bursting of the shell to assure against failures. Indeed, if desired, relatively approximate amounts of silicon can be utilized in the said ignition mixture without the need for precise measuring and handling.

Thus, as seen in the following tabulation, aluminum employed in a concentration of 3% in a lead-selenium ignition mixture functions without setting up a violent reaction. However, when 3.5%, and 4% aluminum are employed, failure can take place as result of the violent reaction with bursting of the cap shell.

Test	Ignition Powder	Number of Caps Shot	Results	Failures, percent
1	Pb-Se	180	8 failed ¹	4.4
2	Pb-Se/Al, 99/1	100	All shot	0.0
3	Pb-Se/Al, 97/3	75	do	0.0
4	Pb-Se/Al, 96.5/3.5	20	1 failed ¹	5.0
5	Pb-Se/Al, 96/4	10	4 failed ²	40.0

¹ Ignition powder burned but failed to generate sufficient heat to ignite the fuse.

² Ignition powder burned so violently that the shell was forcibly ruptured and the delay fuse was not ignited.

With reference to Example 3 hereinabove, it is seen that concentrations of silicon as high as 5% gave no violent reaction. Similarly, silicon concentrations as high as 20% and higher can be employed as described hereinabove, in no event there occurring failure resulting from violent reaction involving silicon.

The foregoing clearly illustrates the nonequivalency of silicon with flame-producing metals such as aluminum and magnesium in ignition mixtures of this invention.

In one embodiment of the method of this invention, an ignition mixture comprising lead, selenium and silicon as described herein is placed in a delay cap superposed on a suitable delay fuse such as barium peroxide-selenium. The fuse is superposed on a suitable primer such as diazodinitrophenol-potassium chlorate, the latter superposed on a high crystalline explosive such as PETN. A resistance or bridge wire is disposed in the ignition mixture and is connected by leg wires to any suitable current source. Current is then passed through the bridge wire and heat is developed responsive to which the primer is detonated, in turn detonating the PETN.

It is to be understood that the initiators of this invention are not to be limited to delay initiators, but are also inclusive of instantaneous-type initiators.

As will be evident to those skilled in the art, various modifications can be made or followed, in the light of the foregoing disclosure and discussion, without departing from the spirit or scope of the disclosure or from the scope of the claims.

What I claim and desire to protect by Letters Patent is:

1. An ignition mixture of from 64 to 80 weight percent lead, from 20 to 36 weight percent selenium and containing an amount of silicon at least sufficient to impart increased heat of combustion when said lead and selenium are burned.

2. An ignition mixture consisting essentially, on a weight basis, of from 0.3 to 20 percent silicon, from 64 to 80 percent lead and from 20 to 36 percent selenium.

3. An ignition mixture of claim 2 containing from 1 to 5 weight percent silicon.

4. An ignition mixture of lead and selenium, in substantially a lead:selenium weight ratio of 72.4:27.6 and containing about 2 weight percent silicon.

5. In an electric initiating device having in combination a delay fuse element and a loose ignition mixture of lead and selenium in contact with the said delay fuse

element, the improvement providing as said ignition mixture, on a weight basis, from 64-80% lead, from 20-36% selenium and from 0.3 to 20% silicon.

5 6. A method for effecting detonation of a primer composition in a blasting cap comprising placing an ignition mixture of lead, selenium and silicon in communication with said primer, in said cap, so as to effect detonation of said primer responsive to heat formed when said mixture is burned, said ignition mixture containing an amount of silicon at least sufficient to impart increased heat of combustion when said lead and selenium are burned, and igniting said mixture.

10 7. A method of claim 6 wherein said ignition mixture is superposed on a delay fuse, said delay fuse being superposed on said primer.

8. A method of claim 6 wherein said ignition mixture is superposed on said primer.

9. A method of claim 6 wherein said mixture is ignited by heat from a resistance wire in contact therewith, developed by passage of electric current through said wire.

10 10. A method of claim 6 wherein said mixture contains from 0.3 to 20 weight percent silicon.

11. A method of claim 10 wherein said mixture contains from 1 to 5 weight percent silicon.

12. A method of claim 10 wherein said ignition mixture contains lead and selenium in substantially a lead:selenium weight ratio of 72.4:27.6 and about 2 weight percent silicon.

13. A method of claim 10 wherein said ignition mixture contains from about 64 to 80 weight percent lead, 20 to 36 weight percent selenium.

14. A delay electric initiating device having in combination a delay fuse element and a loose ignition mixture of lead, selenium and silicon in contact with the delay fuse element, the said ignition mixture consisting essentially, on a weight basis, of from 64 to 80 percent lead, from 20 to 36 percent selenium and an amount of silicon at least sufficient to impart increased heat of combustion when said lead and selenium are burned.

15. An initiating device comprising in combination a loose ignition mixture of lead, selenium and silicon in communication with a primer which detonates in response to being heated, so as to cause said primer to

45 detonate in response to heat generated when said ignition mixture is burned, said ignition mixture consisting essentially, on a weight basis, of from 64 to 80 percent lead and from 20 to 36 percent selenium and containing an amount of silicon at least sufficient to impart increased heat of combustion when said lead and selenium are burned.

16. An initiating device of claim 15 wherein said ignition mixture is in direct contact with said primer.

17. A device of claim 15 wherein said ignition mixture contains from 0.3 to 20 weight percent silicon.

18. A device of claim 15 wherein said ignition mixture contains from 1 to 5 weight percent silicon.

19. A device of claim 15 wherein said mixture contains lead and selenium in substantially a lead:selenium weight ratio of 72.4:27.6 and about 2 weight percent silicon.
